UNITED STATES PATENT OFFICE.

WILLIAM PORTER DREAPER, OF LONDON, ENGLAND.

SPINNING AND TWISTING OF STRANDS OF ARTIFICIAL SILK AND OTHER YARNS OR THREADS.

Application filed May 2, 1922. Serial No. 557,819.

To all whom it may concern:

Be it known that I, WILLIAM PORTER DREAPER, a subject of the King of Great Britain, residing at London, England, have invented new and useful Improvements Relating to the Spinning and Twisting of Strands of Artificial Silk and Other Yarns or Threads, of which the following is a specification.

10 This invention relates to improvements in the spinning of strands of filaments or fibres and particularly those known as artificial silk or the like.

15 According to my invention, for the purpose of imparting a twist to each of the strands of filaments or fibres forming the yarn before they are twisted together to form the yarn by the action of a centrifugal box, the several strands are first kept 20 apart for example by passing them through or over individual guides, guider tubes or passages, and are then allowed to meet and pass into a common guide such as a guider tube or ring, on their way to the centrifugal box, which may be of any suitable diameter. The centrifugal box and the common guider or the whole system of individual and common guiders may be reciprocated relatively to each other in a known 25 manner in the direction of the axis of the centrifugal box. Moreover, during the spinning, a stream of liquid may be advantageously supplied to the individual or to the common guider tube or to both the individual and the common guider tubes, in 30 cases where tubes or enclosed passages are employed. By the improved method of spinning it is possible, for example, to secure in one operation the twisting of composite yarns and also the twisting of the 35 strands making up the same, so that the latter remain separate and do not form a single and larger twisted strand, as they would otherwise do. Thus a composite yarn may 40 be formed for example from two or more 45 untwisted strands of artificial silk filaments, just as they are formed in a spinning bath or otherwise. This obviates any subsequent 50 doubling and twisting operations heretofore required for producing a composite yarn from an ordinary artificial silk thread or strand. Also by working in this way finer 55 filaments or strands can be operated as the strands are immediately twisted and doubled or brought together into a larger composite

strand or yarn, and in this way also the reduction of output which generally accompanies the production of a finer strand of artificial silk is obviated so far as collection in a centrifugal box is concerned. For instance a doubled 200 denier artificial silk yarn may be produced consisting of two 100 denier untwisted strands, which result could ordinarily only be produced by spinning a 60 100 denier strand, twisting this and then 65 doubling the said strand and then again twisting it. There is also a considerable saving in waste due to damage and loss caused by handling in these several operations and consequently a saving in the cost 70 of production.

75 In the accompanying drawing:—

Figure 1 is a vertical section partly in elevation showing one form of apparatus for carrying the invention into practice.

Figures 2 and 3 are central sections illustrating modified forms of the lower end of the common guider tube.

Figures 4 and 5 are vertical sections of modified forms of composite guider tube 80 suitable for my invention.

Figures 6 and 7 are transverse sections of the guider-tube in Figure 5.

Figures 8, 9, 10 and 12 are vertical sections of further modified forms of guider.

85 Figure 11 is a side elevation of the arrangement shown in Figure 10.

The two strands A, B of artificial silk to be treated are preferably produced side by side from two jets as these operate in the usual spinning bath or otherwise. Any known form of jet may be employed. In cases where revolving jets are used, the direction of rotation of the jet is preferably 90 the reverse to that produced by the centrifugal box. The two simultaneously produced strands are led separately out of the precipitating bath (where this is used) and, are then preferably passed over a common godet or drawing off wheel C, so that the 95 rate of delivery of the two strands is identical. Each strand is then separately guided, for example, it passes separately down a special passage in a divided funnel, or alternatively down a separate funnel, and, whilst separate from each other, the strands receive an individual twist. They then 100 meet and are twisted together to form the composite yarn which passes into the centrifugal box D. In such twisting together 105 110

of the strands into a composite thread, the individual strands are further twisted on themselves.

In the apparatus shown in Figure 1, the 5 strands A, B pass into the funnels or guider tubes E, F respectively. These tubes converge at their lower ends and deliver the strands into a common conical guider tube G having an outwardly curved lower end. 10 The three tubes E, F, G are fixed in a frame H, so as to maintain them in the same positions relatively to each other. The tubes E, F are preferably provided with internal annular ribs or beads J, J to reduce the 15 friction between the strands and the interior walls of the tubes. Moreover provision is preferably made for supplying a continuous stream of liquid to each of the funnels, for example through pipes K, K 20 as in the specification of my former application Serial No. 515378.

In order to distribute the twisted two-strand yarn uniformly on the interior of the box D, provision is made in a suitable 25 known manner for moving the frame H and box D relatively to each other. Preferably the vertical movement should be operated by a cam motion, arranged so as to obtain a uniform thickness of the tubular cake in 30 the centrifugal box.

In Figure 2 a bell-shaped end L of the common guider-tube G is shown.

Figure 3 shows a trumpet-shaped end M to this guider-tube, which is here of somewhat larger diameter than that shown in 35 Figure 1.

By keeping the strands apart as they leave the godet wheel it is found that the twisting that takes place by the action of 40 the centrifugal box, will extend to the single strands above the point where they come together to form a single multiple-strand yarn and in this way a preliminary twisting of the single strands is obtained which 45 prevents the strands joining up into a larger single strand, as they would do if not kept apart.

Actual trials will indicate the proper 50 lengths of the funnels and their respective positions and angle of approach, or the distance from one another of their separate parts. These differences are influenced mainly by the speed at which the centrifugal box is rotated and the speed of the 55 godet wheel. Where the second and lower guider is not used the single guiders E', F' may be joined or led at a suitable angle into a common and lower stock or tube N, as shown in Figure 4, in which case special 60 care must be taken to have the respective lengths of the single upper guiders E', F' such that the required action can take place.

By using a specially designed funnel and by taking care that the strands do not come together until they come within the region

where the spinning effect is in operation, it may be possible to work with a single funnel, but this is not advisable. In this case the funnel shaped top end O, of the guider may have a cross piece P set across it as 70 shown in Figure 5 and each strand may pass down a different side of the cross-piece. Also the form of the funnel may be modified i. e. it may be flattened out as shown at O in Figure 6, so that the strands tend 75 to keep apart as they pass down the opposite sides of this flattened guider.

In Figure 8, the upper and lower guiders E'', F'' and G'' are rigidly connected together, and in Figure 9 the upper guiders 80 E, F are arranged in holes in an india rubber or other stopper Q, detachably secured in the cylindrical upper end R of the funnel of the lower guider G.

In Figures 10 and 11 an arrangement is 85 shown in which the individual guider tubes E, F are stationary and the lower and common guider G' is mounted on a frame S adapted to slide vertically on guides T, T and to be reciprocated by a rotary cam V 90 acting on a roller V' on the frame S so as to distribute the yarn equally over the inner wall of the centrifugal box W.

Figure 12 shows a similar construction to that shown in Figures 10 and 11 except that 95 the lower guider tube is replaced by a ring Y supported by means of arms Z, Z on the reciprocatory frame S'.

Also the upper guiders on the centrifugal box side of the godet may be dispensed with 100 and the individual strands taken directly from the godet to the place where they meet and above the common guider. In this case they are maintained in their correct positions on the godet by passing them through guide-eyes, such as those shown at 3, 3 in Figure 1, 105 arranged on the precipitating bath side of the godet.

Where more than two strands are used, 110 corresponding means must be taken to secure the same results. In cases where a composite yarn is desired, and where this is made up of say artificial silk and natural silk or cotton, it is necessary that care be taken that the rate of delivery of the latter is accurately matched with that of the artificial silk and in this case it is advisable that the natural yarn shall be run off a bobbin and over the same godet and thus be drawn off at the same rate as the artificial silk strands with which it is to be formed into a composite strand.

In some cases moreover, it may be advantageous to use individual guider tubes of different lengths.

In the case where the artificial silk strands are produced without the aid of a precipitating bath the strands issuing from two or more jets are led in the same way down a guider or guiders and treated in much the

same manner as the other strands. Especially in this case but generally where required it may be advantageous to pass a steady stream of a suitable solution or a suitable liquid down the funnel guiders during this composite spinning.

What I claim is:

1. An apparatus for producing a yarn from a plurality of strands of artificial fibres, filaments or the like, said apparatus comprising guides for conducting the individual strands to a point where they meet and are twisted together into a yarn, a common annular guide for such yarn, means for simultaneously twisting the yarn and drawing it through the common guide, and means for supplying a continuous stream of liquid to the yarn during its passage through said common guide.
2. A process of producing a yarn from a plurality of strands of artificial fibres, filaments or the like, consisting in simultaneously twisting and drawing the individual strands to a point where they are allowed to meet and to be twisted together, guiding the twisted strands in a substantially straight line to a point at a distance from that at which they meet and then laterally, applying by centrifugal force to the laterally extending part of the yarn, and applying a continuous stream of liquid to the yarn during its passage from the point at which the strands meet to the point at which the twisted strands extend laterally.
3. An apparatus for producing a yarn from a plurality of strands of artificial fibres, filaments or the like, said apparatus comprising guides for conducting the individual strands to a point where they meet and are twisted together into a yarn, a common annular guide for such yarn, a centrifugal box for simultaneously twisting the yarn and drawing it through the annular guide, means for reciprocating the common guide and centrifugal box relatively to each other along the axis of the box, and means for supplying a continuous stream of liquid to the yarn during its passage through said common guide.
4. An apparatus for producing a yarn from a plurality of strands of artificial fibres, filaments or the like, said apparatus comprising guides for conducting the individual strands to a point where they meet and are twisted together into a yarn, a common annular guide for such yarn, a centrifugal box for simultaneously twisting the yarn and drawing it through the annular guide, means for reciprocating the common guide and centrifugal box relatively to each other along the axis of the box, and means for supplying liquid in a continuous stream to the material as it passes the individual and common guides.
5. An apparatus for producing a yarn from a plurality of strands of artificial fibres, filaments or the like, said apparatus comprising annular guides for conducting the individual strands to a point where they meet and are twisted together into a yarn, a common annular guide for such yarn, means for connecting said individual and common guides together, a centrifugal box for simultaneously twisting the yarn and drawing it through the common guide, and means for reciprocating the system of connected guides and the centrifugal box relatively to each other along the axis of the box.
6. An apparatus for producing a yarn from a plurality of strands of artificial fibres, filaments or the like, said apparatus comprising annular guides for conducting the individual strands to a point where they meet and are twisted together into a yarn, a common annular guide for such yarn, means for connecting said individual and common guides together, a centrifugal box for simultaneously twisting the yarn and drawing it through the common guide, means for reciprocating the system of connected guides and the centrifugal box relatively to each other along the axis of the box, and means for supplying liquid in a continuous stream to said individual and common guides.
